[57] CLAIM

The ornamental design for an emergency warning light
base, as shown and described.

DESCRIPTION

FIG. 1 is a front elevational view of an emergency
warning light base showing our new design, with the
broken line showing for illustrative purposes only and
forming no part of the claimed design;

FIG. 2 is a rear elevational view thereof;

FIG. 3 is a right-side elevational view thereof;

FIG. 4 is a left-side elevational view thereof;

FIG. 5 is a bottom plan view thereof; and,

FIG. 6 is a top plan view thereof.

FIG. 1

FIG. 2

FIG. 3

FIG. 4

FIG. 5

FIG. 6
